UNITED STATES PATENT OFFICE.

ELISHA N. FALES, OF DAYTON, OHIO.

FAN.

Application filed May 24, 1920. Serial No. 383,768.

To all whom it may concern:

Be it known that I, ELISHA N. FALES, a citizen of the United States, residing at Dayton, in the county of Montgomery and State of Ohio, have invented new and useful Improvements in Fans, of which the following is a specification.

This invention relates to improvements in fans, and more especially to that type of small high speed rotating fan, usually electric, used in homes and offices for cooling and ventilating.

The ordinary fan referred to above produces a narrow high speed air blast. It has been found that such a blast of air has but little effect on adjacent air lying just outside of the blast itself. The cooling effects are felt only by objects lying directly in the air streams, and there, in most cases, the high velocity of the air has undesirable effects. It is obvious that the field of influence of such a fan is limited by the width of the air stream produced. In most cases, where a larger more diffused blast of more slowly moving air was desired it was thought necessary, heretofore, to use a larger slow speed fan with longer blades, or provide means for oscillating the fan. Such fans are objectionable on account of their extra cost and the larger amount of space occupied.

One of the principal objects of my invention is to produce a small high speed rotating fan which will give a diffused blast of slowly moving air in the form of an expanding cone, or flattened wedge as desired; thus eliminating the annoying effects of a strong blast of air and extending the field of influence of the fan without increasing its size.

The objects of my invention referred to above and others will appear more fully as I proceed with my specification.

In the forms of device embodying the features of my invention and shown in the accompanying drawings, Fig. 1, is a front plan view of a fan adapted to produce a diffused blast of air in the form of a flattened wedge. Fig. 2, is a sectional view on the line 4 of Fig. 1. Fig. 3, is a view similar to Fig. 1 showing a modified form. Fig. 4 is a sectional view on the line 6 of Fig. 3. In Fig. 5 is shown for illustrated purposes, in operation, an ordinary fan without a shroud. Figs. 6 and 7 show a modified form of fan with a continuous shroud composed

of separate segments. Figs. 8, 9 and 10 are vertical sectional views showing different forms of shrouds.

As shown in said drawings, 20 indicates the motor housing of a fan of ordinary construction, the pedestal being indicated by 21, 22 is the shaft on the projecting end of which is mounted in any suitable manner the hub 23 carrying the blades 24. In the various views and modified forms these parts of the fan are indicated by identical reference numerals.

In Fig. 1, I have shown a shroud with two sections removed. In other words, the shroud in Fig. 1 is formed by two segments indicated by 36, each extending approximately 90° of the entire fan blade periphery and arranged diametrically opposite each other. As viewed in Fig. 1 the rotation of the fan is clockwise, one of the segments 36 extending from the top, in a clockwise direction for 90° and the other arranged diametrically opposite.

In Fig. 3 I have shown a fan similar in all respects to the one shown in Fig. 1, except that the shroud segments as indicated in general by 46 are formed of the cylindrical surfaces 47 and the plane surfaces 48 at right angles thereto at the back.

The typical air blast from an ordinary fan without a shroud as shown in Fig. 10 increases its velocity and contracts after leaving the fan blades, and, especially, near to the fan, it becomes a concentrated stream, the energy due to its motion being localized in a comparatively small diameter. With the fans shown in Figs. 1 and 7 the blast produced is more diffused, diverging as it leaves the fan. The shroud prevents the air from flowing inward rapidly at the blade tips as it normally tends to do. The constricted intake area also prevents air from flowing into the fan at the tips, and lets air reach it only from the rear. The rotating blades of the fan exert a centrifugal blower action on the air, with a tendency to throw the air radially outwards. This tendency is offset in the ordinary fan (see Fig. 5) by the momentum of the radially in-flowing air at the tips of the fan blades. When this inflowing air at the blade tips is cut off by the shroud, the centrifugal force will predominate.

In the devices shown in Figs. 1 and 3 where sections of the shroud are removed, the air at these sections flows into the fan radially, and in a more or less normal way.

The combination of the normal flow at these sections with the diverging flow caused by the shroud segments gives a flattened wedge shaped discharge blast. Since the air is somewhat whirled by the fan the shroud segments must not be placed opposite each other at the same height if horizontally disposed flattened wedge shaped blast is desired; but the shroud segments must be given a "lead" or placed out of the horizontal as shown in the drawings. Their exact position will depend on their shape, size and subtended angle.

In Figs. 6 and 7 I have shown a fan with a shroud 26 which is formed of four independent separately removable segments each extending 90° of the entire circumference.

When the segments are all in place a continuous shroud is formed. If desired, two segments may be removed as shown in Fig. 7, making a fan similar to the one shown in Fig. 1 adapted to give a flattened wedge shaped blast.

In Figs. 8, 9, and 10, I have shown different forms that the shroud may take. In each case, I have indicated the shroud by the reference numeral 97.

In the various views, the direction of air currents is indicated by the arrows.

Although I have shown certain devices embodying the features of my invention, it is obvious that, without detracting from the spirit of my invention, many variations in

the form and construction may be made. For example, the fans may be manufactured and sold as a whole, or merely shrouds or segments of shrouds adapted for attachment to existing fans may be made. Also, many and various methods of attaching the shrouds and segments may be used. They may be attached to the motor housing as shown, or to the pedestal, or to the ordinary wire guard which is found on most fans. It is obvious also that, without detracting from the spirit of my invention, the shrouds and segments may be used with or without the ordinary wire guards. It is obvious also that any form of continuous shroud may be fastened to the four blades and rotate with them.

It is my intention to claim in the appended claims all novelty inherent in my invention as broadly as possible in view of the prior art.

What I claim as new and desire to secure by Letters Patent is:

1. A fan with circular segments of a shroud lying outside the blade tips substantially as shown.
2. A fan with a circular shroud composed of independently removal segments surrounding the blade tips.
3. A fan with segments of a substantially frusto-conical shaped shroud surrounding the blade tips.

In testimony whereof I have hereunto set my hand and seal this 6th day of May, 1920.

ELISHA N. FALES. [L.S.]
